UNITED STATES PATENT OFFICE.

WILLIAM T. RIGHTMYER, OF MERIDEN, CONNECTICUT.

PEN.

SPECIFICATION forming part of Letters Patent No. 296,456, dated April 8, 1884.

Application filed May 26, 1883. (No model.)

To all whom it may concern:

Be it known that I, WILLIAM T. RIGHTMYER, of Meriden, in the county of New Haven and State of Connecticut, have invented a 5 certain new and useful Improvement in Pens, of which the following is a specification.

The object of my improvement is to produce a pen having a slotted concavo-convex nib, as I believe that a pen of that character will afford greater facility for writing than one having angular nibs.

My improvement consists of a pen having a concavo-convex nib, the upper surface of which is concaved longitudinally of the pen 15 and the under surface or contact-point convexed.

In the accompanying drawings, Figure 1 is a side view of a pen embodying my improvement. Fig. 2 is a section of the same, taken 20 transversely through the nibs; and Fig. 3 is a side view of a pen of modified form, and of a holder.

Similar letters of reference designate corresponding parts in all the figures.

25 A designates the shank or body of the pen, and B designates the nibs thereof. This pen may be made of steel or other suitable metal.

The pen shown in Figs. 1 and 2 is of the usual form in respect to its nibs being approximately in line with the body, but the pen shown in Fig. 3 has the nibs and adjacent portion bent out of line with the shank or body, so that when the shank or body is inserted in a holder of ordinary size, the nibs will be opposite the center of the holder. A holder, C, 35

is shown in dotted lines in this figure, to illustrate the position which the nibs of the pen will occupy with relation to the holder. The pens shown in all the figures have their nibs bent into concavo-convex form, as shown more 40 particularly in Fig. 2, the nib portion being rounded on both sides in the form of a hollow cylinder.

In making a pen embodying the improvement, I first form a blank in the ordinary or 45 any other approved manner, but make the nib portion wider than the width which the nibs are to have when the pen is completed. After this blank is completed, the nib portion is bent into concavo-convex form, and subsequently 50 it is slotted centrally in the usual manner with shears or otherwise.

A pen embodying my improvement will be less liable to catch in the paper than a pen 55 having angular nibs, and hence can be moved with greater facility in a variety of directions as it approximates to a lead-pencil point.

What I claim as my invention, and desire to secure by Letters Patent, is—

The writing-pen herein described, provided 60 with a slotted concavo-convex nib or point, the upper surface of which is concaved longitudinally of the pen, and the under surface or contact-point convexed, as and for the purposes herein specified.

WM. T. RIGHTMYER.
